UNITED STATES PATENT OFFICE.

FRANK E. BOCORSELSKI, OF RICHMOND, VIRGINIA.

FUEL-FEEDER.

1,131,988.

Specification of Letters Patent. Patented Mar. 16, 1915.

Application filed March 14, 1914. Serial No. 824,759.

To all whom it may concern:

Be it known that I, FRANK E. BOCORSELSKI, a citizen of the United States of America, residing at Richmond, in the county of 5 Henrico and State of Virginia, have invented certain new and useful Improvements in Fuel-Feeders, of which the following is a specification.

This invention relates to fuel feeders, and 10 its primary object is to provide a feeder especially adapted for feeding pulverized fuel, so constructed as to insure the maximum degree of combustion of the fuel, and the elimination of waste by leakage during 15 the passage of the fuel from the feed hopper to the furnace.

A further object of the invention is to 20 provide an apparatus for feeding pulverized fuel to a furnace by the aid of a fluid blast, preferably an air blast, so constructed as to direct the blast against the fuel while the latter is in suspension, or in the form of a falling stream, as it passes into the receiving feed conduit or passage, and to expel 25 the same through the passage outlet.

A further object of the invention is to 30 provide a fuel feeder so constructed that any fuel entering the feed passage which may escape the action of the blast, so as not to be discharged through the discharge end of said passage, will drop by gravity into a suitable bucket, and be returned to said passage, thus avoiding loss by leakage, or 35 the escape of droppings from the feeder, which is a source of expense and annoyance in the use of feeders, unprovided with means for guarding against loss from that cause.

A further object of the invention is to 40 provide the fuel passage of the feeder with means for retarding the flow of the pulverized fuel in such a manner as to prevent the dropping of the fuel through the passage so quickly as to escape the desired full action of the air blast to expel it. This too 45 direct or sudden dropping of the fuel is liable to occur, especially when the fuel is damp, or more or less coagulated.

The present invention is distinguished 50 from the prior art, mainly by reason of the fact that in the operation of the improved feeder, the air blast employed in charging the furnace contacts with the pulverized fuel while the latter is in the form of a falling stream, or suspended in the air within 55 the feed passage, in its travel from the inlet to the outlet of said passage.

The invention thus briefly outlined might be embodied in various mechanical constructions, differing in detail, but the embodiment shown in the accompanying drawings, 60 which form a part of this specification, has been found successful in the important points of simplicity and durability, as well as effectiveness in operation.

The construction of the feeder will be 65 fully described in connection with the drawings, and its features of novelty set forth, and defined in the appended claims.

In the drawings:—Figure 1 is a side elevation of a fuel feeder embodying the invention. Fig. 2 is a horizontal section of the same on an enlarged scale taken on the line 2—2 of Fig. 1. Fig. 3 is a view in perspective of the revoluble disk and its radially-disposed blades, removed from the casing. Fig. 4 is a vertical transverse section of the feeder, showing baffles within the fuel passage for the purpose above described. Fig. 5 is a detail transverse section of the casing with the revoluble disk and blades 80 removed therefrom, and Fig. 6 is a detail horizontal section on the line 6—6 of Fig. 4.

The reference numeral 1 designates a base, supporting standards 2, upon which is secured a hollow casing 3 of cylindrical form, 85 having an integral head 4 at one end, and an annular outwardly-projecting flange 5 at its opposite end to which is secured by bolts or like fastenings 6 a closure disk 7. Projecting inward from the disk 7 is a circular hollow casing comprising circular outer walls 8, and inner parallel straight walls 9, the space 10 between the walls 9 constituting a fuel passage through which the fuel passes to a position in line with a sleeve 11 90 projecting centrally from the outer side of a revoluble disk 12 and having mounted thereon a worm wheel 13 meshing with a worm 14 mounted upon the shaft 15 of a suitable motor 16. The sleeve 11 extends 100 through a tubular boss 17 projecting from the head 4 of the casing in parallel relation to the sleeve 11, and between the outer surface of the sleeve 11, and the inner periphery 18 of the boss 17 are interposed roller 105 bearings 19 to permit an easy revolution of the disk 12 and sleeve 11, the boss 17 serving as the axial support. Projecting radially from the inner face of the disk 12 are a plurality of equi-distant blades 20 secured at 110 their outer ends in any suitable manner to the disk, and preferably having their inner

ends secured to an annulus 21 to revolve within the inner periphery of the casing.

The casing 3 is provided with an opening 22 communicating with the lower end of a feed chute 23 depending from a hopper 24, secured to the casing 3, or forming a part thereof. A pipe 26 leading from any suitable source of compressed air supply, a blower, or the like, is fitted into the outer 10 end of the sleeve 11 to direct a blast through the space 10. Adjacent to the lower delivery end of the chute 23, the casing 3 is provided with yielding packings 25 to prevent the dropping of fuel between the buckets 15 and the wall of the chute. These packings 25 are preferably secured by insetting them in recesses provided for their reception in the walls of the casing, as best shown in Fig. 4.

20 To prevent the pulverized fuel from dropping through the passage 10 too rapidly, its flow is retarded by means of inclined deflecting baffle plates 10^a, disposed transversely within the passage 10. Below the 25 downwardly inclined plates 10^a are provided two confronting baffles 10^b projecting from the opposite walls of the passage, and oppositely-inclined as shown to provide a contracted throat 10^c through which the passage of the fuel will be retarded as is obvious, to insure its being acted upon by the air blast.

The operation of the device constructed as above described, will be readily understood. The rotation of the motor shaft 15 revolves the disk 12 and its sleeve 11 and blades 20 through the worm gearing shown, and each pair of adjacent blades (Fig. 3) form a bucket 27 to receive pulverized fuel 40 from the chute 23. When the bucket 27, by the revolution of the disk, reaches a position opposite the upper end of the passage 10, its contents drop through said opening in a fine stream, and when it reaches a point 45 opposite the open end of the passage, and the pipe 26, the air blast strikes the falling stream at the point 28, substantially midway the length of the passage 10, and discharges it into the furnace, as will be readily understood by those skilled in the art to which the invention relates.

While the blast is ordinarily sufficient to discharge all of the finely-divided fuel held in suspension within the passage, any surplus particles not discharged by the blast will fall through the lower end of the passage 10 and be caught by one of the buckets revolving thereunder, as will be readily understood from the illustration in Fig. 4.

50 It is obvious that the feeder as an entirety is adapted to be secured to a furnace door, or in such position with relation thereto, as to make the charging of the furnace a continuous operation as long as the motor is 55 operated.

Having thus fully described my invention and in what manner the same is designed for use, what I claim as new and desire to secure by Letters Patent is:—

1. A fuel feeder comprising a stationary casing provided with a diametrically-disposed fuel passage, and a fuel inlet, a series of radially-arranged revoluble buckets adapted to successively receive fuel through said inlet, means for directing a fluid blast 75 against the stream of fuel in its travel through said passage, and means for retarding the movement of the fuel through the passage.

2. A fuel feeder comprising a stationary 80 casing provided with a diametrically-disposed fuel passage, and a fuel inlet, a series of radially-arranged revoluble buckets adapted to successively receive fuel through said inlet, means for directing a fluid blast 85 against the stream of fuel in its travel through said passage, and means for retarding the movement of the fuel through the passage consisting of obstructions arranged therein.

90 3. A fuel feeder comprising a stationary casing provided with a diametrically-disposed fuel passage, and a fuel inlet, a series of radially-arranged revoluble buckets adapted to successively receive fuel through 95 said inlet, means for directing a fluid blast against the stream of fuel in its travel through said passage, and means for retarding the movement of the fuel through the passage consisting of baffles projecting 100 from the walls of the passage.

4. A fuel feeder comprising a stationary casing provided with a diametrically-disposed fuel passage, and a fuel inlet, a series of radially-arranged revoluble buckets 105 adapted to successively receive fuel through said inlet, means for directing a fluid blast against the stream of fuel in its travel through said passage, and means for retarding the movement of the fuel through 110 the passage consisting of baffle plates projecting from the opposite walls of the passage, and inclined toward each other.

5. A fuel feeder comprising a stationary 115 casing provided with a diametrically-disposed fuel passage, and a fuel inlet, a series of radially-arranged revoluble buckets adapted to successively receive fuel through said inlet, means for directing a fluid blast against the stream of fuel in its travel 120 through said passage, and means for retarding the movement of the fuel through the passage consisting of inclined baffle plates projecting from the opposite walls of the passage, and extending throughout 125 the length of the passage.

6. A fuel feeder comprising a stationary casing provided with a diametrically-disposed fuel passage, and a fuel inlet, a series of radially-arranged revoluble buckets 130

adapted to successively receive fuel through said inlet, means for directing a fluid blast against the stream of fuel in its travel through said passage, and means for retarding the movement of the fuel through the passage consisting of a pair of baffle plates projecting from opposite walls of the passage and inclining toward each other, and a second pair of baffles below the first-named pair, confronting each other to provide a throat through which the fuel passes.

7. In a fuel feeder, the combination with a stationary circular casing having at one side a closure disk provided with a central discharge opening, and a hollow circular casing projecting from said disk formed with a diametrically-extending fuel passage, and at its opposite side with a head having a hollow boss, of a disk within said stationary casing provided with radially-projecting blades to form fuel-receiving buckets, and with a sleeve projecting within said boss, roller bearings between said boss and sleeve, a worm wheel mounted on said sleeve, a motor shaft, and a worm therein in gear with said worm wheel.

8. In a fuel feeder, the combination with a stationary outer casing provided with a peripheral fuel inlet, and a hollow circular inner casing provided with a diametrically-extending fuel passage open at its ends, of a hopper communicating with the fuel

inlet, a revolute disk within said outer casing having a sleeve open at its ends projecting centrally from one face of the disk, 35 and a series of radial blades projecting from the opposite face of the disk at the periphery thereof and forming fuel-receiving buckets, and a blast pipe connecting with said sleeve.

9. In a fuel feeder, the combination with a circular outer casing provided with a peripheral fuel inlet, and a hollow circular inner casing provided with a diametrically-extending fuel passage open at its ends, 45 of a hopper communicating with said inlet, a revolute disk within said outer casing having a sleeve open at both its ends and projecting centrally from one side thereof, a series of radial blades projecting from the 50 opposite side of said disk adjacent the periphery thereof and forming fuel-receiving buckets, and a blast pipe for directing a blast through said sleeve to strike the falling stream of fuel at a point mid-way the 55 length of the said fuel passage and discharge it through a central opening in the casing aligned with said sleeve.

In testimony whereof I affix my signature in presence of two witnesses.

FRANK E. BOCORSELSKI.
